BASE FOR TROPHIES

Alfred John Flauder, Trumbull, Conn., assignor to Alexander M. Pistey, Bridgeport, Conn.

Application December 22, 1955, Serial No. 39,441

Term of patent 7 years

(Cl. D29—23)

FIG. 1.FIG. 2.FIG. 3.

Fig. 1 is a front elevational view of a base for trophies, showing my new design;

Fig. 2 is an end elevational view thereof; and

Fig. 3 is a top plan view thereof.

The rear elevational view is the same as Fig. 1 and the opposite end of Fig. 2 is the same as the view shown.

I claim:

The ornamental design for a base for trophies, as shown and described.
